PORTABLE SPIN DRYER

Thomas R. Smith, Frank E. Ross, and William J. Swartz,
Newton, Iowa, assignors to The Maytag Company,
Newton, Iowa

Filed July 5, 1972, Ser. No. 269,281

Term of patent 14 years

Int. Cl. D15—05

U.S. Cl. D49—1 A

FIG. 1 is an elevation view of the portable spin dryer showing our new design;

FIG. 2 is a top view of the portable spin dryer of FIG. 1; and

FIG. 3 is a section view showing the contour of one rib as taken along line 3—3 of FIG. 1.

The portable spin dryer as viewed from the right, left and rear of FIG. 1 is substantially the same in appearance as the view shown.

We claim:

The ornamental design for a portable spin dryer, as shown and described.
